UNITED STATES PATENT OFFICE

EDWARD F. McDONALD, OF BUFFALO, NEW YORK, ASSIGNOR TO FARIES MANUFACTURING COMPANY, OF DECATUR, ILLINOIS

DESIGN FOR A SMOKER STAND

Application filed November 23, 1931. Serial No. 41,809. Term of patent 14 years.

To all whom it may concern:

Be it known that I, EDWARD F. McDONALD, a citizen of the United States, residing at Buffalo, in the county of Erie and State of New York, have invented a new, original, and ornamental Design for Smoker Stands, of which the following is a specification, reference being had to the accompanying drawing forming a part thereof.

The figure of drawing is a perspective view of a smoker stand showing my new design.

I claim:

The ornamental design for a smoker stand, as shown.

EDWARD F. McDONALD.
